UNITED STATES PATENT OFFICE

ISAAC A. BAUM, OF CHICAGO, ILLINOIS

METAL FRAME

Application filed May 16, 1929. Serial No. 363,444.

My invention relates to metal frames for wall openings and particularly to an improvement in door frame construction adapted to eliminate the cracking of the plaster at a point adjacent to the opening.

Notwithstanding the most rigid mounting of metal frames on the tile or other walls, there is a tendency toward cracking of the plaster at some point adjacent to the point between the frame and the wall. The slamming of heavy doors results in a deflection and vibration, which, however small, is transmitted to the plaster, and, as the plaster is non-resilient, a crack is likely to result.

By means of the improvement here disclosed, I provide for a division line in the plaster utilizing a pair of back-to-back plaster terminals that are not connected. In fact, I provide a separate plaster section as a part of the frame structure and this section is free to move with the frame without affecting the main joint of plaster.

The invention will be more readily understood by reference to the accompanying drawings, in which

Fig. 1 is a sectional perspective view showing the frame as applied to a wall and before the plaster has been applied; and

Fig. 2 is a sectional view showing a completed structure after plaster has been applied.

In the drawings, I have illustrated a frame of generally channel shape having a web 10, constituting a jamb, a door strip 11 and side flanges 12, 13. The structure shown is intended for application to an outside wall, in which case there is but one line of plaster, that is, plaster is applied only to the interior wall. It will be understood, however, that where used on an interior wall, the provision for eliminating cracking will be applied to both flanges.

A tile or other wall is indicated at 14, the channel frame being mounted thereover. Wood inserts 15 may be inserted at intervals in the joints between the tile to receive nails 16 passing through the base 17 of a plaster terminal strip. The strip has a perpendicular flange 18, the margin of which is rebent as at 19.

Secured to the flange 12 of the channel frame by welding or otherwise, are two oppositely disposed L-shaped terminal strips or plaster beads 20, 21 the outside strips being placed at a desired distance from the face of the jamb and moulded for decorative purposes if occasion requires. The inner or rearward strip is secured to a point near the inner edge or margin of the flange so that the plaster space between the pair of strips is substantially equal to the depth of the flange. The strips 19, 21 are preferably in abutting relation but are not attached. Thus any movement of the frame is not transmitted to the point 22 of plaster. The small amount of exposed surface at the edge of the plaster terminal strips 19, 21 may be painted and will not be unsightly.

As a means for anchoring the plaster I provide the anchor loops 23 struck out from the flange 12 of the channel and the loops 24 struck out from the flange 12 of the channel and the loops 24 struck out from the base 17. A wall anchor for the channel frame is indicated at 25 and is in the form of a bail having hooked ends that engage with the frame as shown.

In operation the frame with its attached parts being installed and the tile wall laid, the plaster terminal member 17, 18 is nailed in proper position and the plastering carried on in the usual manner.

Obviously, the construction may be modified to a certain degree, and I do not wish to be limited except as indicated in the appended claims.

I claim:

1. In combination, a channel shaped frame, a continuous plaster bead secured to a flange of the channel near the face or web of the channel, a second bead secured to the flange near the rear edge thereof and a third bead abutting the second bead and secured to the wall in which the frame is mounted.

2. In combination, a channel shaped door frame, a pair of L-shaped strips having their bases welded to the outer face of a flange of the channel, the perpendicular flanges of the strips having their margins rebent oppositely inwardly thereby defining a plaster receiving

- space of substantially the width of the flange, and a third L-shaped strip having its base secured to a wall within which the frame is mounted and with its flange in sliding engagement with the corresponding flange of the rearward strip of said pair.
3. In combination, a metal frame adapted to contact a wall, a pair of flanged plaster terminal strips secured to said frame, and a third plaster terminal strip adapted to be secured to the wall, said last named strip being independent of said frame and having the perpendicular flange thereof in contact with the similar flange on the rearward of the two plaster terminals first mentioned.
4. In combination, a metal frame adapted to contact a wall, a pair of flanged plaster terminal strips secured to said frame, and a third plaster terminal strip adapted to be secured to the wall, said last named strip being independent of said frame and having the perpendicular flange thereof in contact with the similar flange on the rearward of the two plaster terminals first mentioned, the margins of said plaster terminals being rebent to provide a plaster anchor.
5. In combination, a metal frame adapted to contact a wall, a pair of flanged plaster terminal strips secured to said frame, and a third plaster terminal strip adapted to be secured to the wall, said last named strip being independent of said frame and having the perpendicular flange thereof in contact with the similar flange on the rearward of the two plaster terminals first mentioned, the margins of said plaster terminals being rebent to provide a plaster anchor, the rebent anchor on the margin of the first two plaster terminals being disposed toward each other.
- 40 In testimony whereof I have affixed my signature.

ISAAC A. BAUM.
